AUTO TOP

Jules A. Olivier, Detroit, Mich., assignor to Dietrich, Incorporated, Detroit, Mich., a corporation of Michigan

Application May 9, 1930, Serial No. 450,939

3 Claims. (Cl. 296—107)

This invention relates to collapsible vehicle tops, and particularly to the means by which they are collapsed and stowed away.

One object of this invention is to provide a vehicle top that will be neat in appearance, and appear solid and permanent when up in its raised position.

Another object is to provide a vehicle top that will be completely invisible, when down in its collapsed position, so stowed away, that the rear deck of the body is substantially clear and uninterrupted, the streamline lines of the body are unbroken, and the place where the top has entered is substantially invisible thus giving the car a neat shipshape appearance with clean stream lines, not only when the top is up, but also when it is down.

Another object is to provide a strong terminal edge to the top material.

Another object is to form a weather-tight seal around the edge of the top where it touches the body.

Another object is to provide suitable holding means for securing the top to the body in weather-tight relation.

Another object is to provide a top that will fold more compactly than previous tops and take up less space when folded.

Another object is to provide a neat ship-shape, substantially waterproof, sunproof and dustproof case, into which the top may be stowed, where it will be protected from the ravages of the elements.

Another object is to provide a cover for such a case that is made of the same material as the body and is hinged thereto, and which when closed forms a streamline continuation of the body, giving the vehicle a neat appearance.

Another object is to provide a weather tight seal around the edge of such a cover so that when it is closed water and dust cannot enter the compartment adapted to contain the folded top, and to construct such a weather seal in a simple and practical manner to provide a cheap and yet positive sealing means.

Another object is to provide a manipulating, locking, and hold-down means, for such a sealing means, having a neat appearing operating handle or knob and adapted to lock and unlock the cover and compress the sealing means into sealing relation with the body or release it from such relation, by simple rotation of the knob in alternate opposite directions, and to provide cheap, simple and yet substantial and positive means to accomplish these results.

Another object is to give this weatherproof case such position, outline and construction so that it will conform to the stream-line lines of the vehicle, and will add to, rather than detract from, the general appearance of the vehicle as a whole.

Another object is to provide a top that is easily handled, is strong and substantial, and when collapsed and folded away will protect the covering material of the top from excessive bending, stretching, or other stresses.

Another object is to provide a vehicle top that is very simple in construction with few parts, the parts themselves being simple and easily fabricated, so as to provide a strong substantial top, that is also collapsible, at a relatively low cost of manufacture.

Numerous other objects and features of novelty will be apparent, upon reading the specification and accompanying drawings, in which an illustrative embodiment of this invention is shown, in which:

Fig. 1 is an elevation, with parts broken away to show details of construction, of an automobile in which is mounted an illustrative form of my invention with the top raised.

Fig. 2 is a fragmentary elevation of the same automobile with the top lowered and stowed away.

Fig. 3 is a fragmentary plan view of Fig. 2.

Fig. 4 is a cross-section of Fig. 1 taken on a vertical plane along the longitudinal axis of the automobile.

Fig. 5 is cross-sectional view of a portion of Fig. 3 taken along the line 5—5 looking in the direction indicated.

Fig. 6 is a cross-sectional view of a portion of Fig. 2 taken along the line 6—6 looking in the direction indicated.

Fig. 7 is an enlarged elevation in cross-section of the hold-down means for the rear top material holder indicated as 109 in Fig. 4.

Fig. 8 is a plan view of the spring retainer indicated as 112 in Figs. 7 and 9.

Fig. 9 is an enlarged view of a portion of Fig. 4 at the point where the top is attached to the windshield, showing details of construction.

Fig. 10 is a fragmentary constructional plan view of Fig. 4 showing in dotted lines intermediate positions of the top as it is folded up.

Fig. 11 is a fragmentary cross-sectional view taken along the line 11—11 of Fig. 4 showing the construction of the auxiliary spring cover with the top raised.

Fig. 12 is a fragmentary cross-sectional view

taken along the line 12—12 of Fig. 3 looking in the direction indicated, showing the cover with the top lowered and stowed away.

Fig. 13 is a fragmentary cross-sectional view of 5 Fig. 3 taken along the line 13—13 looking in the direction indicated, showing the overlap of the main and auxiliary covers.

Fig. 14 is a fragmentary cross-sectional view taken along the line 14—14 of Fig. 3 looking in 10 the direction indicated, showing the cover in closed position and showing the weather tight sealing means and the locking means for the cover.

In Fig. 4 an automobile body 1 is provided at 15 the rear edge of the door frame at each side of the body with vertical frame members 2 and 3 to which the front ends of horizontally disposed rearwardly extending frame members 4 and 6 are secured.

20 A transverse frame member 1 is connected to the members 4 and 6. Mounted rigidly on these frame members is an open topped, U-shaped, top container box 8 composed of vertical sides 9, 11 and 12, and horizontal floor 13. A hinged cover 14 composed of horizontal frame members 16 and 17, transverse frame members 18 and 19 and body covering material 21 fastened to the frame members is provided for closing the top of the container.

25 Secured to transverse frame member 1, are 30 a pair of spaced horizontal brackets 22 and 23 of identical construction to which hinge members 24 and 26 are pivotally mounted by pivot pins 27 and 28, respectively. These hinge members 35 carry the cover 14, supporting the rear edge 19 thereof when in lowered position and limiting the opening movement of the cover by means of the bowed portions 29 coming against the transverse frame member 7.

40 The rear sides of the top ends of the vertical frame members 2 and 3 have horizontally extending brackets 31 and 32 rigidly secured thereto. The brackets 31 and 32 pivotally support the lower ends of a main top bow 33 by means of 45 pivot pins 34 and 36.

45 On the rear side near the lower ends of main top bow 33 are horizontal lugs 37 and 38 to which are pivotally mounted links 39 and 41, and pivotally mounted on the ends of said links is secondary top bow 42. The purpose of these pivots and links is to allow the lower end of secondary top bow 42 to swing around in the dotted line 50 path 43 so as to shorten its effective length to that of the main top bow when it is lowered into 55 the top container 8.

50 When in raised position as shown in Fig. 4, the tension in top material 44 causes secondary top bow 42 to force links 39 and 41 in a forward direction until transverse extensions of pivot pins 60 46 and 47 rest against main top bow 33 which limits the travel of links 39 and 41.

55 Holding the main top bow 33 braced in an upright position from the body are a pair of folding braces consisting of longitudinal elements 49, 50, 51, and 55 connected by hinges 52 and 60. The rear end of these braces are pivotally secured to the rear top material holder 98 and the forward ends are pivotally secured to the main top bow 33.

60 Near the upper ends of the rear faces of main top bow 33 are two pairs outstanding horizontally disposed lugs 53, 54, 56, and 57 which extend rearwardly and contain a pivot pin 58 which swingingly support a pair of forward extending brace

members 59 and 61. The function of this pivoted support is to allow folding movement of the brace members, as shown in Fig. 10, in dotted line parts 63 and 64 which are progressive points in the folding movement.

Extending horizontally forward from pivot pins 58 and 59 on lugs 53, 54, 56, and 57 of the main top bow 33, are a pair of forward brace members composed of longitudinal members 59, 61, 62, and 66 hingedly connected to intermediate 10 link members 67 and 68 by means of hinge pins 69, 71, 72, and 73. The forward longitudinal members 62 and 66 are pivotally connected to intermediate members 74 and 76 by means of pivot pins 77 and 78, the function of the pivoted connections being to allow the collapse of the longitudinal brace members as shown in Fig. 10.

This brace means is made collapsible so that it may fold up through the dotted line positions 63 and 64 in Fig. 10 and go into the top container 20 8 as shown in Fig. 5.

Hinged to the intermediate members 74 and 76 by means of hinge pins 79 and 81 are vertically disposed half hinges 82 and 83 which are securely mounted at the rear of both ends of forward top material holder 84.

These hinges 77, 78, 79, and 81 are to allow the forward top material holder 84 to swing around into the dotted line position 86 as the top is collapsed so it can fit into the top container in the 30 position shown in Fig. 5.

The forward top material holder 84 has the forward end of top material 44 firmly secured thereto and is mounted by means of holes 87 and 88 and set screws 89 and 91 on an upstanding rib 93 integrally formed on the top side of the windshield support frame 96.

The forward top material holder is detachably secured to the windshield support frame in order that it may be detached therefrom and folded 40 back with the remainder of the top into the top container.

The windshield support frame 96 is securely mounted on a forward part of the body 1 and supports the windshield glass 97 as well as the forward top material holder.

On an extension of transverse pivot pins 34 and 36 (which are mounted on horizontal brackets 31 and 33, secured to vertical body frame members 2 and 3) is pivotally mounted U-shaped horizontally extending rear top material holder 98 which passes up, out openings 99 and 101 and runs around the rear deck upon the top of top container cover 21. The rear top material holder consists of a rigid member 98 which is firmly surrounded by a hem 102 in the lower edge 103 of top material 44 which is fastened back on itself at 104 by cementing or sewing or otherwise fastening the material together.

Similarly fastened to material 103 is material 106 which is formed with a hem 107 in which is firmly held a tube 108 of rubber or other elastic or deformable material. This tube is so positioned as to be between the rigid member 98 and the deck 21 of the top container cover 14 to 65 seal out water as will be explained later on.

At one or more points in its length rigid member 98 has lugs 109 extending horizontally and inwardly therefrom, and having a wing bolt 111 retained by retaining member 112 in swiveled relation in opening 113 of the lug.

In the top container cover 14 are openings 114 which pass through deck 21 and horizontal frame members 16. A bushing 115 is set in this hole from the top until the shoulder on flange 116 of 75

the bushing seats on the deck 21 and the lower end of sleeve 115 is near the lower end of the opening 114.

The bore 117 of this bushing has a screw thread and a bolt 118 having a washer 119 on its shank is screwed upwardly into the bore closing the bore and drawing the bushing tightly into place in opening 114.

- 10 Wing bolt 111 is adapted to be screwed downwardly into the top of vertical threaded bore 117 of bushing 114 so as to draw horizontal lug 109 and rigid member 98 down toward deck 21 so as to deform and compress tube 108 which closes the space between rigid member 98 and deck 21 completely and without injury to the high finish on deck 21 (which is enameled or otherwise finished in a similar manner to the rest of the body surface), thus sealing off and preventing rain, wind, water and dust from passing under 20 the rear of top material 44.

In Fig. 14 is shown an enlarged view of the sealing and locking means for the cover 14.

Extending completely around the internal upper peripheral edge of the top container compartment 8, with the exception of the portions of the ends of the U-shaped arms covered by the auxiliary covers 121 and 122 (to be described further on in this specification) and with the exception of short interruptions to allow the passage of hinge members 24 and 26, is a sealing flange 128.

This metal flange 128 is fastened rigidly to the body frame members, such as 129, by suitable means such as screws 131, and has an outwardly spaced upwardly projecting terminal edge 132 adapted to engage a rubber strip gasket 133 to seal the compartment 8.

Mounted in a channel in the lower surface and near the outer peripheral edge of the frame members, such as 18, of the cover 14 is a rubber strip gasket 133. This gasket is compressed against flange 128 by means of a locking means consisting of a cylindrical bushing 134 having a circumferential flange 136 and secured rigidly in cover frame member 18. The bushing 134 has a rectangular opening 137 in its wall. A sleeve 138 is mounted in the bore of the bushing for rotation through a right angle by means of a pin 139 mounted on the sleeve and extending into the rectangular opening in the bushing. Extending radially out from the sleeve is a lug 141 adapted to catch under flange 128 at one extreme of the right angle movement. A nut 142 is spot-welded or soldered to the sleeve concentric to the bore 55 thereof.

Extending through the bores of the sleeve and bushing and having a manipulating knob 143 on its upper end is a screw-threaded rod 144 threaded in nut 142 and having its end deformed at 146 to prevent removal therefrom.

In Figs. 11, 12, and 13 the auxiliary covers are shown in detail.

Pivotal mounted immediately inside of main top bow 33 on each side of the body 1 are auxiliary covers 121 and 122 which are spring pressed by helical torsion springs 123 and 124 against main top bow 33 and which follow the main top bow automatically as it is lowered down into the top container 8, whereupon the auxiliary covers cover the openings 99 and 101 out of which rear top material holder and main top bow formerly projected. The main top cover has upturned flanges 124 and 126 which fit under overhanging flanges 127 and 128 to complete the weather-tight sealing 75 of the top container 8.

The operation is as follows:

To lower the top from the raised position shown in Fig. 1, to the collapsed and stowed away position shown in Fig. 2, the operator unscrews wing bolts 111 until they clear the bore 117 of bushings 114. Then he rotates knob 143 counterclockwise, which causes latch 144 to unscrew downwardly until clear of flange 128, whereupon friction will cause latch arm 141 to swing counterclockwise out of the way of flange 128 as pin 139 moves in opening 137. This releases the cover. Then he raises rear top material holder 98 up until it raises secondary top bow 42 high enough to allow him to swing U-shaped top container cover 14 up to its raised and open position and he opens the top container.

Dropping the rear top material holder down into the container he proceeds to the front of the car and loosens set screws 89 and 91 until he can raise front top material holder 84 off the upstanding rib 93. He then folds brace members 59, 61, 62, and 66 by pushing them inwards at their midpoints and collapses the front of the top towards the back up to the main top bow 33, the front top material holder dropping to position 86 as the top material gets some slack in it.

He then bends hinges 52 and 68 and collapsing brace means 49, 50, 51, and 55, slowly lowers the whole top until it rests entirely within the container as shown in Fig. 2, the auxiliary top container covers 121 and 122 following the main top bow 33 down, urged by helical torsion springs 123 and 125 until they close openings 99 and 101 which are at the extreme ends of the arms of U-shaped top container 8.

He then lowers the U-shaped top container cover 14 which forms a continuation of the rear deck of the vehicle and which completely covers the remainder of the opening and the operation is complete.

To raise the top the same general process is gone through in reverse order.

The combination and construction of the collapsible frame members for the top constitute an important feature of the invention and are particularly designed to fold together so that in collapsed position they will occupy very little space. The front header member or material holder 84 and the side rails which connect it with the main bow 33 are so constructed and arranged and attached to the main bow as to fold into a position between the sides of the main bow, thus materially reducing the thickness of the bow stack when the top is folded. This is accomplished by mounting the rear ends of the side rail members on vertical pivots which permit the rails to fold inwardly between the vertical sides of the bow and also by providing vertical joints in the rails in their mid portions so that they may fold upon themselves and providing both vertical and horizontal pivots for the header member so that it may fold downwardly relative to the side rails and thereby lay forwardly of them when in folded position and between the sides of the main bow member. As illustrated in Figure 5, the rear intermediate bow 42 is connected by links to the lower side portions of the main bow 33 whereby the links may fold relatively to the main bow to bring the outer portion of the intermediate bow 42 directly beneath that of the main bow 33 when in folded position. The rear terminal bow or material holder 98 is shorter than the main bow 33 and is curved to conform to the contour of the body surface and when in folded position lies forwardly of the out-

er portions of the bow members 33 and 42 as shown in Figure 5. The diagonal brace members 49 and 51 are also specially arranged to lend to the compactness of the top. They are connected at one end to the sides of the main bow and at their other ends to the sides of the rear terminal bow or material holder 98 and thus do not interfere with or require special openings to be made in the pocket cover 21. It has been conventional practice to attach the rear ends of such bracing members to the side frame members of the body. In such cases it is necessary to provide special openings in the cover for the top receiving pocket to accommodate the braces when the top is in raised position. In my construction all of the collapsible members are connected in one compact unit which is secured at the single point 34 to the vehicle body making these the only points at which separate cover arrangements must be made for the top receiving pocket.

The advantages of this invention are numerous, the main advantages being that the top while raised is strong, substantial, and solid, and will not collapse of its own accord, and that while in the raised position the container is covered at all times by a continuation of the rear deck of the body. It is easily lowered, without damage to the top, into a compact, small space, that does not interfere with the functions of the vehicle or weaken it structurally in any way.

When it is in lowered position, it is completely covered and protected from sun, atmosphere, water, dust and other deleterious agents, and the covering conforms to the stream lines of the body so that there is no unsightly bump, or ridge, or other evidence of where the top is, or was, or has gone.

The little flanges 116 on bushings 114 may be plated with lustrous metal in which case they are decorative, or countersunk and finished as the body of the car, in which case they are invisible.

Numerous other advantages and novel features will be obvious on reading the specification, the drawings and the claims.

The invention is broad in scope and solves the problem of what to do with the top and how to keep the material from being ruined by cracking or rotting when in a lowered position.

Because of this:

The invention does not limit itself to a top for an automobile, as it may be used on a runabout type motor boat, or any other vehicle.

The invention does not limit itself to the exact illustrative form described in the specification and drawings, as numerous modifications and changes of form or detail may obviously be made without departing from the true scope of the invention, which is set forth in the following claims.

I claim:

1. A top frame for a vehicle body comprising a main top bow pivotally connected to the body, folding brace means holding the main top bow in braced relation, a link member pivotally connected to the main top bow, a secondary top bow

pivots connected to the link member, a forward top material holder detachably secured to the body and hingedly secured and held in braced relation to the main top bow by collapsible means, and a rear top material holder pivoted to the body, and detachably secured thereto, and means for securing said holder to the body in sealed relation thereto.

2. In a vehicle body, a collapsible top frame comprising a main bow member pivotally connected at its ends to the intermediate side portions of the body, a forward transverse member, vertically jointed side rails having their rear ends connected by vertical pivots to the upper side portions of said main bow and their forward ends connected by vertical and horizontal pivots to said forward transverse member, a rear intermediate bow member having a pivotal link connection with the lower side portions of said main bow, a rear terminal bow having its ends pivotally connected to the intermediate side portions of said body, and jointed braces each having an end pivotally connected to the intermediate side portions of said main bow and said rear terminal bow.

3. In a vehicle body having an upright windshield at the forward end of the passenger section and an upwardly opening pocket along the rear sides and back of the passenger section, a collapsible top comprising a flexible cover for the rear, sides and top of said passenger section, a collapsible frame for supporting said cover comprising a main bow having its ends pivotally mounted within the forward ends of said pocket and adapted to pivot into and out of the confines of said pocket, a windshield header adapted for releasable attachment to the top of said windshield and supporting the forward end of said cover, vertically jointed side rails having vertical and horizontal pivotal connections with header and having vertical pivotal connection at their rear ends with the upper side portions of said main bow, whereby said side rails and header may be folded and disposed between the sides of said main bow, a rear terminal bow supporting the rear end of said flexible cover and having its ends pivotally mounted within the forward ends of said pocket adjacent the ends of said main bow and adapted to pivot into and out of the confines of said pocket, jointed brace members pivotally connecting the intermediate side portions of said main bow and rear terminal bow, a rearwardly extending intermediate bow, links pivotally connected to the ends of said intermediate bow and to the sides of said main bow whereby the length of said bow may be shortened in folding for disposal in said pocket immediately beneath said main bow, a unitary removable cover for said pocket having an exterior surface corresponding in contour and flush with the exterior surface of said body and providing a support for said rear terminal bow when the top is in raised position.

JULES A. OLIVIER.
